RAZOR

Hermann Hill, Bridgeport, Conn., assignor to
 Magazine Repeating Razor Company, New
 York, N. Y., a corporation of New Jersey

Application March 24, 1939, Serial No. 263,834

5 Claims. (Cl. 30—40)

The invention is most usefully employed when embodied in a razor of the type which houses a stack of blades in the handle and is provided with an injector which successively feeds a blade at a time from the stack into a shaving head which is pivoted at the end of the razor usually on a post projecting therefrom, in such manner that it may be swung to a position with its blade-retaining channel in line with the blade-ejecting orifice of the magazine for the reception of a blade, and transversely of the post for shaving. This general type of razor is illustrated and described, for example, in Schick United States Patent No. 1,797,733. It is nevertheless adaptable to any razor which possess the features of a blade-holding head which swings from one position to another about a pivot.

The broad object of the invention is to make provision in a razor of this type for accurately aligning the blade edge with respect to the guard with which such razors are conventionally provided. More particularly, the object is to make provision in such a razor for stops against which the blade edge abuts when in shaving position and for a construction which will permit the reception of a blade without contact with the stops while the head is in position for receiving a blade from the magazine, but whereby the blade edge will be automatically moved into contact with the stops and thus be accurately aligned with the guard when the head is swung to a position for shaving.

Referring to the drawing:

Fig. 1 is a view of a razor of the type referred to showing the head in position for receiving a blade and a blade in process of injection into the head;

Fig. 2 is a view on the line 2—2 of Fig. 1;

Fig. 3 is a view on the line 3—3 of Fig. 2 but showing certain of the parts in full;

Fig. 4 is a top view with the head in shaving position;

Fig. 5 is a view in elevation and in section through the median transverse plane of the shaving head;

Fig. 6 is an "exploded" view of the component parts of the shaving head.

Referring more in detail to the drawing, the magazine handle of the razor indicated by the numeral 10 is provided with means for successively ejecting blade from a stack contained therein through the blade-ejection slot 11, all of which is a well-known construction but, as an example of specific details of a suitable construction, reference is made to the above-mentioned

United States patent to Schick No. 1,797,733. Since however the details of the magazine handle and the ejecting mechanism do not enter into the invention, I will not further describe them.

5 Proceeding to features which are more closely involved in the invention, the head, the disassembled parts of which are illustrated in Fig. 6, is pivotally mounted on a king-post 12 projecting from the end of the magazine handle 10. In a 10 magazine handle that is square in cross-section like that illustrated, it is desirable for purposes of compactness of construction that the blade ejection orifice be parallel to and closely adjacent to one of the sides but, on the other hand, that, 15 when the head is turned to shaving position as is shown in Fig. 6, the blade be inclined to the vertical axis of the post in order to facilitate use of the implement. Therefore, the pivotal mounting is on an axis that is oblique to the lines of the 20 side walls as shown in Fig. 4, the degree of obliqueness being determined by the shaving angle desired in the particular case. A construction of this nature is shown in the United States Patent to Rodrigues No. 2,060,243, but, since it is not 25 essentially involved in the invention, it will not be further described except to say that the obliqueness is such that, when the head is in non-shaving position (that is, the position shown in Fig. 1), its blade-receiving channel is in registry 30 with the orifice and parallel with the side of the handle, while in shaving position (as shown in Fig. 4), the blade channel of the head is inclined to the vertical axis of the post.

The blade receiving and holding channel is best illustrated in Fig. 5, and its main elements are the blade platform 13 and the spring clamping plate 14. The tension in the clamping plate 14 is, of course, properly adjusted to hold a blade "A" gripped between it and the blade platform 35 with sufficient rigidity and firmness to ensure proper shaving but not to a degree whereby undue resistance will be offered to movement of the blade toward the blade stops—all of which will be presently further explained.

40 45 The actual overall width of the blade receiving channel is determined by the relative positions of the blade stops 15, 15 on the one hand and the abutments 16, 16 on the other, which, for convenience in manufacture, may be merely struck up from the blade platform. Of course, the spacing of the stops 15, 15 with relation to the abutments 16, 16 will be determined from the width of the blades which are to be used in the selected design and as will appear is to be greater 50 55 than the blade width.

The blade platform terminates in a suitable guard 18 and is cut away as shown at 19 to facilitate shaving and to allow for ready cleaning.

The blade platform and the spring clamping plate 14 may be assembled in any suitable way, but by way of illustration it may be done as shown in Figs. 5 and 6. In these figures the kingpost is provided with a pintle 20 on which is rotatably fitted a washer 21 having a reduced portion 22. The plate 17 is provided with an aperture 23 and the plate 24, which is a continuation of the spring clamping plate 14, is provided with an aperture 25, these apertures being of a size to rotatably fit the reduced portion 22 of the washer. The lever 26, which will presently be more particularly described, has an aperture 27 which loosely fits the washer 21 over its larger diameter. The whole is assembled in connection with the kingpost by means of the screw 28 and the washer 29 as shown in Fig. 6. The washer 29 is preferably provided with lugs 30 which enter slots 31 in the pintle 20. This is to prevent back and forth turning of the screw when the head composed of the spring clamping plate 14, blade platform 13, and their connected parts are rotated about their axis for the purpose of changing from shaving position to blade-receiving position, and vice versa.

For greater firmness and rigidity of the head, it is best to extend the upper end of the kingpost so that, when the head is in shaving position, the blade platform bears on it as indicated by 32 in Fig. 5. If necessary for accuracy of registration of the blade-receiving channel with the blade ejection orifice, the material of the bottom plate may be struck out the proper distance as shown by the numeral 33 for contacting with the kingpost at the point of registration.

The lever 26, as shown in the drawing, is in the form of a somewhat oblong washer or collar slightly bent on a transverse axis, thus providing bearing areas 34 and 34', whereby it may rock on the plate 17. When assembled, the plate 17 which is a continuation of the blade platform serves as a bearing surface for the bearing areas, and it will be apparent that, as the lever is rocked on these areas, the tip 35 moves toward and away from the stops 15, 15. The rocking motion of the lever is brought about by the travel of the stud 36 about and on the lower arm 37 of the lever, the lower arm and the stud virtually constituting a cam and cam follower, respectively. As the shaving head is moved to blade-receiving position (as shown in Figs. 1, 2, and 3), the stud passes the bearing area 34, thus leaving one arm of the lever and riding up on the next, thus causing the tip 35 to recede from the stops 15, 15 and thus substantially widen the blade-receiving channel to a width somewhat greater than that of the blade as shown in Fig. 2. The blade-ejection slot 11 is so positioned with relation to the head, or vice versa, that the path of a blade as it emerges therefrom and enters the head takes the position shown in Fig. 2—that is to say, a position in which the edge of the blade is clear of the stops. The purpose of this is obviously to prevent injury to the blade edge as it travels in the blade channel. When, however, the head is tipped to shaving position as shown in Fig. 5, the stud 36 operates on the lower end of the lever, thus rocking it to the position shown in Fig. 5 and at which it is bearing against the rear edge of the blade and forcing the cutting edge against the stops 15, 15. The blade edge is accordingly definitely located with respect to the guard 18 and

this will be true of all blades that may be inserted in the head.

It is desirable that the lever possess some resiliency and that the arms be at such an angle and the other parts be so proportioned that, after the blade edge has abutted the stops (which should take place slightly in advance of full shaving position), further rotation to full shaving position will simply have the effect of pressing the blade edge firmly in abutment with the stops, without however imparting any motion to it.

A return motion of the shaving head from the position shown in Fig. 5 to that shown in Fig. 1 frees the blade from the pressure of the lever, and the entrance of a new blade from the magazine simply drives out the blade already in the head, and the new blade is substituted for it, taking however the position shown in Fig. 2.

The blade platform is cut away as shown at 33 to provide an aperture in which the tip 35 may travel toward and away from the stops. While I prefer that the lever be resilient as I have before described, it is possible to make it rigid, although obviously complete rigidity would introduce the necessity for a degree of precision in manufacture that would be a handicap to production on a quantity basis, and furthermore would serve no useful purpose.

While I have described a certain particular construction in which my invention is incorporated, I do not desire to be limited to this particular embodiment since many changes and modifications may easily be made without departing from the spirit and scope of the invention as set forth in the following claims.

I claim:

1. In a razor of the type comprising a support and a shaving head thereon provided with a guard and adapted to be rotated from a position in line to receive a blade from a blade-ejecting mechanism to a position for shaving, blade-edge abutments located on the head and positioned to locate the edge of a blade with respect to the guard, means in the head providing a blade-retaining channel, a lever with one end projecting into the channel at a point remote from the abutments, and cam means on the support adapted to actuate the other end of said lever as said head is rotated to shaving position to force the edge of a blade in said channel against the abutments, and to operate on the arm of said lever that projects into the channel to release said blade from said abutments as the head is rotated to blade-receiving position, the said lever being fulcrumed between its ends.

2. In a razor of the type comprising a support and a shaving head thereon provided with a guard and adapted to be rotated from a position in line to receive a blade from a blade-ejecting mechanism to a position for shaving, means in the shaving head providing a blade-retaining channel, and a lever with one end projecting into the channel and cam means adapted to actuate the lever on rotation of the head to said shaving position to move the projecting portion of the lever toward the guard, the said cam means operating on the other end of the lever as the head is rotated to blade-receiving position to cause the said projecting portion to recede from the guard, the lever being fulcrumed between its ends.

3. A razor comprising a support for a blade-retaining head, blade-ejection mechanism, a blade-retaining head provided with a guard and with a blade-retaining channel and pivotally

mounted on the support for rotation from a position of registry of the blade-retaining channel with the blade-ejection mechanism to a position for shaving transverse of the support and vice versa, a resiliently yielding lever with one end projecting into the blade-retaining channel at a point remote from the guard, and cam means adapted to actuate the other end of said lever to move its projecting portion toward the guard as the head is rotated to said transverse position and to operate on the arm of said lever that projects into the channel to cause it to recede from the guard as the head is rotated into said position of registry with the blade-ejection mechanism, the said lever being mounted to rock on a fulcrum between its ends.

4. In a razor of the type comprising a support and a shaving head thereon provided with a guard and adapted to be rotated from a position in line to receive a blade from a blade-ejecting mechanism with which the shaving head is associated, to a position for shaving, abutments located on the head and in the vicinity of the guard, means in the head providing a blade-retaining channel, a lever fulcrumed between its ends with one end projecting into the channel at

5 a point remote from the abutments, and cam means adapted and positioned to actuate the opposite end of said lever as said head is rotated to shaving position to force the edge of a blade in said channel against the abutments and to operate on the arm of said lever that projects into the channel to release said blade from said abutments as the head is rotated to blade-receiving position.

10 5. A razor comprising a support for a blade-retaining head, blade-ejection mechanism, a blade-retaining head provided with a guard and with a blade-retaining channel and mounted by means of a pivot on the support for rotation from a position of registry of the blade-retaining channel with the blade-ejection mechanism to a position for shaving transverse of the support and vice versa, a lever in the form of an oblong washer surrounding the pivot and projecting into the blade-retaining channel at a point remote from the guard, and cam means adapted to operate the said lever to move its projecting portion toward the guard as the head is rotated to said transverse position.
